UNITED STATES PATENT OFFICE.

REUBEN R. FINCH, OF PEEKSKILL, NEW YORK, ASSIGNOR TO UNION
STOVE WORKS, OF SAME PLACE.

DESIGN FOR A COOKING-STOVE.

Specification forming part of Design No. 6,685, dated May 27, 1873; application filed May 5, 1873.

To all whom it may concern:

Be it known that I, REUBEN R. FINCH, of Peekskill, in the county of Westchester and State of New York, have invented a new and original Design for Stoves, of which the following is a specification:

My improved design for stoves is fully represented in the accompanying printed illustration. The first part of the said design consists of the concave cornice A, having the raised figures B. The second part consists of the molding C, plain border D, figured border E, and plain inclosed surface F for the doors. The third part consists of the cornice A, with raised figures B, the upper wide doors having the moldings, borders, and plain surface; the lower narrow doors having the same moldings, borders, and plain surface; also the moldings G H between the upper and lower doors, all comprising a design for a stove-front. The fourth part consists of the plain surface I, molding J, plain border L, and figured border M, inclosing the plain panel N; and the fifth part consists of the upper wide panel N and lower narrow panel O, with like borders and moldings above and below the projecting draft, and separated by the moldings G H, all

comprising a design for the side plate of a stove. The sixth part consists of a design for the number-plate P, as shown.

I claim as my invention—

1. The design for the top plate of a stove, substantially as represented at B.
2. The design for a stove-door, substantially as represented at C D E F.
3. A design for a stove-front, comprising the cornice A with figures B, upper and lower doors with moldings C D, borders D E, plain inclosed surfaces F, and the moldings G H between the doors, substantially as specified.
4. The plain surface I, moldings J, plain border L, figured border M, and plain inclosed panel N, substantially as specified.
5. The design for the side plate, comprising the upper wide panel, lower narrow one O, inclosing borders and moldings, and the moldings G H, substantially as specified.
6. The design for the number-plate P, as shown.

REUBEN R. FINCH.
